CHAIR

Nathan George Horwitt and Morris Katcher, New York, N. Y., assignors, by mesne assignments, to Ethel Pinous, New York, N. Y.

Application May 17, 1933, Serial No. 671,436
Renewed August 1, 1935

6 Claims. (Cl. 155—50)

The main object of this invention is to provide a graceful, sturdy, and comfortable chair, economical in construction and conforming to modern methods and standards of manufacture, 5 maintenance and utility.

A further object of this invention is to provide a chair which may be rapidly disassembled and as rapidly assembled to function as a permanent article of furniture.

10 A further object of this invention is to provide a chair whose frame including arms and supports are made of metal forms having both the rigidity and the degree of resilience requisite for full comfort.

15 A further object is to provide a chair with a rigidly held, but quickly adjustable, back.

A further object of this invention is to provide a chair having an open and accessible construction without detracting from appearance and 20 comfort, to facilitate cleaning and repair.

25 A further object is to provide in such a chair a construction which will permit rapid removal and replacement of the seat to facilitate cleaning, renovation, and the like.

30 Other and further objects and advantages of our invention will become apparent from the description, hereinafter, in connection with the drawing, of a preferred embodiment of our invention:

35 In the drawing:

Fig. 1 is a plan view of a chair embodying our invention,

Fig. 2 is a front elevation, and

Fig. 3 is a side elevation of the chair shown 40 in Fig. 1,

Fig. 4 is a detail of the adjustment of the back of the chair

Fig. 5 is a detail of the assembly of the frame and seat.

45 Fig. 6 is a detail, similar to Fig. 5, of a modified assembly of a chair having flat frame elements in place of the round ones shown in Figs. 1 to 5,

Fig. 7 is a side view of the detail shown in Fig. 6.

50 The supporting base and legs are formed, out of a length of steel or metal of similar characteristics which may be easily obtained as a tube, rod or flat strip, to provide a pair of supports 1, 1 at either side of the chair adapted to rest on the floor. At the front the length of material is curved upwardly from 1, as at 2, to provide the "legs" of the chair, and the legs 2 terminate in arms 3 extending backwardly parallel to the base elements 1, 1 for a convenient distance. At the 55 rear the members 1 are connected to each other

by the bar 4, the intermediate portion of the length of tubing out of which the entire supporting structure is formed; so that the portions 1, 4, and 1 together form a roughly quadrangular base resting on the floor. It is obvious that the bar 5 may be omitted and the members 1, 2, 3 at each side of the chair formed separately; but the presence of the bar 4 subserves the useful function of acting to prevent separation or spreading of the rest of the supporting structure. 10

The arms of the chair are constituted by tubes or rods of steel or similar material bent into U-shape and set in a vertical plane, namely, the plane of the corresponding side 1, 2, 3 of the support. The lower leg 6 of the U (which may 15 be designated generically as 5) extends parallel to, above and in juxtaposition to the upper backward extending arm 3 of the supporting structure, and may be held thereto by pins or bolts 7 passing through both 3 and 6. The ends 3 and 20 6 are engaged and clamped in a sleeve 8, split as at 9, and having the edges of the sleeve produced horizontally inward as at 10 and 11 to form a doubled ledge or flange. The seat 12 of the chair is provided preferably with recesses 13 on its 25 undersurface at either side of sufficient size to accommodate the ledge formed by flanges 10 and 11; so that the seat 12 may be readily fitted to rest upon and be supported upon the said ledges. Bolts 14 passing through flanges 10 and 11 and 30 entering the seat 12 serve to tighten the sleeve 8 by drawing the flanges 10 and 11 together; and to hold the seat 12 securely to and on the ledges formed by the flanges 10 and 11. It is to be noted that the sleeve 8 is sufficient to hold the 35 ends 3 and 6 securely together; but the pins 7 are provided partly as an aid to assembly and partly to eliminate the possibility of relative rotation of the ends.

In Fig. 6 and Fig. 7 we have shown a modification adapted to use with a support formed from a flat strip of metal. The ends 3' and 6', corresponding to 3 and 6 of Fig. 5, have their flat faces in contact. Straps running from side to side of the chair support the seat; and the 45 ends 3' and 6' are secured to the ends 25 of the strap by bolts 30. It is to be noted that the strap ends 25 are themselves supported and rest upon the end 6'. The strap is bent down from the end 25 to form a vertical portion 26 50 adjacent to the seat 12' and then continued horizontally as at 28 to the other side of the chair, so that the straps, of which I have shown two as sufficient, though more may be used as found desirable, form a cradle or frame to receive and 55

frictionally hold the seat 12'. Bolts 14' may pass through the straps and enter the bottom of the seat 12' as additional securing means, if desired. A guard or housing 28, split at its inner side for an obvious reason, may be slipped over the ends 3' and 8'.

The back of the seat is formed of a padded or upholstered member 15 having a substantially circular cross-section and provided with forwardly extending arms 16, 16, adapted to receive in channels or recesses 17 the backwardly extending arms 18 of the U 5. The arms 16 and 18 are secured to each other by means of the pawl 19, pivoted as at 20 in a recess on the under side of the arm 16, and having a nose 21 engaged in one or other of a longitudinal series of holes or notches 22 in arm 18. A spring 23 mounted in arm 16 and operating against the thumb end 24 of pawl 19 urges the nose 21 of the latter into engagement with the hole 22.

The arms 16 and 18 co-operate to form an arm rest which may be upholstered or otherwise treated or finished for a variety of purposes. The back may be adjusted by releasing the pawl 25 19 and sliding the former backwards or forwards along the arms 18.

The seat 12 forms a substantially independent unit and may be quickly removed, and as quickly replaced, upon the removal or insertion of the bolts 14. The whole chair may then be rapidly disassembled by withdrawing the back 15 from engagement with the arms 18, slipping off the sleeve 8 and removing the pins 7. Reassembly involves the same simple operations in reverse order.

The preferred material for the base and arms is steel tubing of a dimension sufficient to support the weight of the occupant of the chair with only a perceptible amount of resilience. This slight give of the chair is necessary for full comfort. Where a higher degree of resilience is desired we prefer to use the flat, spring shape shown in Figs. 6 and 7.

The structural independence of the back and seat, and of the several elements of the chair, permit their removal for repair, renovation, re-upholstering and the like. The open framework renders every part easily accessible for cleaning and repair; and the construction necessitates only elements that are fully and completely functional thus preserving in combination with simplicity of the structure the highly aesthetic effect so desirable in articles of furniture.

We claim:

55 1. A chair comprising a seat, a support member formed with a backwardly projecting arm at each side of the seat, a back and arm rest mem-

ber provided with backwardly extending arms adjacent the previously recited arms, and means engaging and holding together adjacent arms said means having provisions for supporting the seat.

2. A chair comprising a seat, a support for the chair formed with backwardly projecting arms in the vicinity of the seat, a back and arm rest member provided with downwardly and backwardly projecting arms adjacent the previously recited arms, and means comprising a split sleeve receiving adjacent arms, and means cooperating with the seat for tightening the sleeve to clamp and hold the said arms together.

3. A chair comprising a seat, a support for the chair formed with backwardly extending arms in the vicinity of the seat, a back and arm rest member provided with downwardly and backwardly extending arms adjacent the previously mentioned arms, a split sleeve receiving adjacent arms, the edges of said sleeve at the split being flanged to provide a support for the seat, and means cooperating with the seat to draw the flanged edges together whereby the said sleeve may be tightened to clamp and hold securely together the said arms.

4. A chair comprising a seat, a support member provided with ground engaging portions and with backwardly extending arms at each side of the seat, a back and arm rest member provided with backwardly extending arms adjacent the previously mentioned arms, and means secured to and extending from one pair of adjacent arms to the other pair of adjacent arms and providing a support for the seat.

5. A chair comprising a seat, U-shaped members providing legs and supports for the chair and having the bights of the U's at the front, U-shaped members providing arms for the chair and having the bights at the front, the upper limb of each leg U extending adjacent the lower limb of an arm U, means for holding together the adjacent extending limbs, said means having provisions for supporting the seat.

6. In a chair a back and arm member in the form of a U with forwardly extending limbs, the bight of the U forming the back rest of the chair and the forwardly extending limbs the arm rests, supports for the back and arm member comprising vertically mounted U-shaped members having their upper limbs engaged with the forwardly extending limbs of the back and arm member, and means for adjusting the position of the back and arm member upon the support members.

NATHAN GEORGE HORWITT.
MORRIS KATCHER.
